UNITED STATES PATENT OFFICE.

WILLIAM GURDEN HALSEY AND JOHN CURRIER, OF ORANGE, NEW JERSEY.

APPARATUS FOR GRINDING AND POLISHING TUBULAR ARTICLES, &c.

Specification of Letters Patent. Patented Jan. 10, 1911.

981,417.

Application filed September 30, 1910. Serial No. 584,651.

To all whom it may concern:

Be it known that we, WILLIAM GURDEN HALSEY and JOHN CURRIER, citizens of the United States, and residents of Orange, in the county of Essex and State of New Jersey, have invented certain new and useful Improvements in Apparatus for Grinding and Polishing Tubular Articles, &c., of which the following is a specification.

This invention relates to apparatus for grinding, polishing or cleaning tubes, pipes or rods, and the like, composed either of porcelain, metal, or other material, and has for its object the provision of polishing means which are capable of adjustment within reasonable limits, so as to insure a uniform grinding, polishing, or cleaning action, upon the articles treated, irrespective of their diameter, and also to permit of the application of varying degrees of pressure upon the said articles which are subjected to the grinding, polishing, or cleaning action. Moreover, the apparatus may be so constructed as to permit of the grinding, smoothing and buffing of articles, such as metallic rods, in a single, continuous operation, in the same apparatus, or the separate steps may be performed successively in different apparatus.

The invention is particularly described and set forth in the following specification and the accompanying drawings forming a part thereof, in which,

Figure 1 is a vertical section of the apparatus showing the tube operated upon in elevation; Fig. 2 is a plan view, partially broken away, showing the said tubes in section within the apparatus; Fig. 3 is a longitudinal elevation of a combination apparatus for accomplishing the grinding, smoothing and buffing of pipes, rods, etc. continuously; and Fig. 4 is a composite view showing the different types of friction elements which may be employed.

Referring to the drawings, the numerals 1, 1, represent sectional brush-backs which are removably and adjustably mounted between end-plates 2, 2, being mounted in slots 2', 2'. The said brush-backs are secured thereto by nuts 3, threaded on to bolts 4 which project from the said brush-backs. Each of the brush-backs is provided with bristle tufts A, A, which are arranged to frictionally engage an article, for example, an unglazed porcelain tube B (suitable for

filtering apparatus). As shown the said individual brush-backs may be adjusted to conform to the diameter of the articles to be subjected to the grinding, polishing, or cleaning operation. Preferably a circular brush-block 1' is secured within the collar 5 which projects from the lower end-piece 2, the said circular brush-block being removably secured within the collar by means of a locking-screw a, and having upwardly extending bristle tufts A', which serve to receive the lower end of an article such as the tube B. This circular brush-block constitutes an elastic support for the article inserted in the apparatus, with the result that all risk or possibility of fracture of fragile articles, due to contact with the end-piece, is eliminated. A shaft or journal 6 is secured to the collar 5, preferably being integral therewith, and this is provided on its outer end with a beveled-gear element 7 which is arranged to mesh with a co-acting beveled-gear 8 and to be rotated thereby in the manner well known. The said shaft is adapted to rotate within the journal 9 having a flanged upper end 9' and an annular elastic, or other suitable washer, 10, which is adapted to seal the same against the admission of liquid through said bearing into contact with the shaft 6.

The reference letter C designates the bottom of a sink, or other receptacle, in which the said shaft is mounted, the bearing 9 being secured thereto by means of a gasket 11 and a nut 11', as shown.

A shell or drum D, which is adapted to fit in an annular groove b in the bottom C of the receptacle, serves to prevent the centrifugal ejection of liquid during the rotation of the brush element, and consequently results in the liquid X, which only partially fills the said shell when the apparatus is at rest, serving to completely fill the same during rotation thereof, owing to its inability to escape horizontally and the consequent vertical rise of the same until it attains the upper edge of the shell.

The reference numeral E designates a holder, such as a pair of tongues, or the like, for gripping the tube B during the insertion and withdrawal of the same from the apparatus.

In order that a substantially uniform and continuous pressure may be applied to the articles treated, irrespective of whether the

friction element consists of bristles of wire or animal fiber, or carborundum, emery, or the like, we equip the brush-back with springs, preferably leaf springs, such as indicated by the numerals y , y , the same being screwed to the brush-backs at one end and abutting against an annular flange $2'$ formed on the respective end-plates 2 , 2 . In order to retain the tension of said springs 10 at any desired degree adjusting screws y' , y' are threaded into the said flanges 2 , $2'$, the same extending therethrough and contacting with the said leaf springs y , y , whereby the slightest inward movement of the screws 15 will increase the tension of said springs in the manner well known. It is evident that when the adjusting nuts 3 are tightened, the action of the springs will be rendered inoperative; and when employing bristles for 20 the friction element, such as hog-bristles or wire bristles, the action of the springs is usually unnecessary. However, when employing carborundum, emery, and like friction elements, the said nuts 3 are loosened 25 in order that the action of the springs will not be destroyed, as would be the case were the nuts tightened as aforesaid.

In order that each friction element may be accurately adjusted to exactly the same 30 relative position with respect to the article treated as is an adjoining friction element, the marginal portions of each of the slots $2'$ are calibrated as designated by the reference letter Z , and the outer ends of the bolts 4 , as 35 shown are scored in order to provide an indicator and to enable one to accurately adjust the said bolts along the said slots.

In Fig. 3 is illustrated a form of apparatus suitable for the treatment of piping, 40 rods, etc., in a continuous manner without removal from the apparatus. This consists of a sectional rotary grinding member 1^2 which corresponds with the sectional brush-back 1 except that the circular end-piece 1^1 is dispensed with, and in lieu of bristles tufts 45 the friction element consists of emery or carborundum secured in any suitable manner to the sectional backs of the grinding member. A smoothing member 1^3 , which corresponds with, and is secured to a common 50 hollow shaft with said grinding member, is provided with an elastic friction element, such as wire bristles of fine piano wire, brass wire, or the like, and a polishing member 1^4 , also secured to a common shaft with the 55 other two members, corresponds with the aforesaid member except that the friction element is of soft material such as felt or cotton, or some such material capable of 60 serving as a buffing or polishing material. A belt 13 which is adapted to be connected with a suitable shafting is reeved around a pulley 14 secured to said hollow shaft 12 , and serves to rotate the respective grinding, 65 smoothing, and polishing member si-

multaneously, and thereby an article, such as a tube B' , which is supported upon travelers 15 , 15 , can be successively ground or reduced, smoothed and finely polished without removal from the apparatus.

In Fig. 4 is illustrated a fragmentary composite view of the different friction elements in elevation, in order to indicate the various elements which may be employed in the apparatus for carrying out the operation in a continuous manner. The reference numeral 1 designates the brush-back shown in Fig. 1, which carries tufts of hog-bristles A , whereas the number 1^1 designates a corresponding brush-back which is provided with an emery or carborundum grinding element or shoe A^1 . Similarly the reference numeral 1^2 represents a brush-back carrying wire bristles A^2 suitable for smoothing a tube after the preliminary grinding treatment, whereas the brush-back 1^4 which carries a felt buffing element A^4 serves for the purpose of completing the final polishing of tubing or the like.

The operation of cleaning porcelain tubes, 90 such for example, as the unglazed porcelain tubes used for the so-called "Pasteur" filters, as distinguished from the continuous treatment of tubes above described, can be conveniently and economically performed in this apparatus with a minimum risk of breakage and a minimum amount of erosion consistent with perfect cleansing. The operation is easily performed by merely setting the support 2 in rotation, it being understood of course that the individual brush-backs A are first adjusted to conform to the size of the tube to be cleansed, and then the tube is gripped in a pair of tongs, or merely with the fingers if desired, and inserted 95 within the central aperture of the apparatus as shown in Fig. 1. In actual operation there seems to be a tendency for the brushes to draw the tube inwardly when once the same is inserted in between the uppermost bristles, provided the same are adjusted so that the aperture between the ends of the respective bristles of the opposing brush-backs is a trifle less than the cross-section of said tube, preferably about $\frac{1}{32}$ of an inch less. 100 This automatic drawing in of the tube can of course be rendered more positive or pronounced if the bristle tufts are so arranged that the path from one bristle tuft to the corresponding tufts of each individual brush-back is substantially spiral, in which event it is apparent that the rotation of the support in one direction will draw the tube inwardly and when drawn in the opposite direction will tend to eject the same, provided of course the tube be held against rotation, by the tongs or other means with which it is gripped, while inserting or withdrawing the same.

Having thus described our invention what 130

we claim and desire to secure by United States Letters Patent is:

- 5 1. The combination consisting of a plurality of spaced supports, a plurality of individual members secured at opposite ends to each of said supports, and each member being disposed intermediate said supports and radially adjustable with respect to the centers of each of said supports, said members being disposed around but distant from the centers of said supports, and each of said members being provided with marginal friction elements which extend along substantially the entire length thereof and which project inwardly from their respective inner faces, whereby a central aperture is formed suitable for the reception of an article to be polished or ground, and means for rotating said supports simultaneously.
- 10 15 20 2. The combination consisting of a plurality of spaced supports, a plurality of elastically mounted individual members secured at opposite ends to each of said supports,

and each member being disposed intermediate said supports and radially adjustable 25 with respect to the centers of each of said supports, said members being disposed around but distant from the centers of said supports, and each of said members being provided with marginal friction elements 30 which extend along substantially the entire length thereof and which project inwardly from their respective inner faces, whereby a central aperture is formed suitable for the reception of an article to be polished or 35 ground, and means for rotating said supports simultaneously.

Signed at Orange, in the county of Essex and State of New Jersey this 28th day of September A. D. 1910.

WILLIAM GURDEN HALSEY.
JOHN CURRIER.
